UNITED STATES PATENT OFFICE.

JOSEPH J. MARSH, OF DECORAH, IOWA.

POST-OFFICE FURNITURE.

SPECIFICATION forming part of Letters Patent No. 764,299, dated July 5, 1904.

Application filed April 7, 1904. Serial No. 202,118. (No model.)

To all whom it may concern:

Be it known that I, JOSEPH J. MARSH, a citizen of the United States, residing at Decorah, in the county of Winneshiek and State of Iowa, have invented certain new and useful Improvements in Post-Office Furniture, of which the following is a specification.

My invention relates to post-office furniture, and is especially adapted for use in assorting 10 newspapers for individual delivery.

It is customary in distributing newspapers and periodicals by mail from the office of publication to the various subscribers to send them in bulk packages with no separate wrap- 15 per provided for the individual papers there- in to post-offices located in populous centers, each paper contained in the package having the individual address of the subscriber for whom it is intended stamped in a suitable 20 manner thereon. The bulk packages are then opened by the post-office employees and the various papers assorted for delivery to the sub- scribers as per the specific address thereon. In assorting these unwrapped papers through 25 the medium of the usual pigeon-hole case they are constantly mutilated and damaged, often tearing off portions or blurring the ex- posed pages to such an extent as to be unread- able. It is the object of my invention to ob- 30 viate this objection; and to this end it consists in the details of construction and in the ar- rangement and combination of parts to be hereinafter more fully set forth and claimed.

In describing the invention in detail refer- 35 ence will be had to the accompanying drawings, which form part of this specification and wherein like characters of reference denote corresponding parts in the several views, and in which—

Figure 1 is a side elevation of my invention; Fig. 2, an end view; Fig. 3, a plan view; Fig. 4, a longitudinal vertical section on the line *aa* of Fig. 3, with the hinged septa removed; Fig. 5, a transverse section on the line *bb* of Fig. 3, and Fig. 6 a detail view of one of the 45 septa.

Referring to the drawings, A represents a base provided with suitable supports A', and preferably closed on three sides by the end

pieces A² A³ and the side piece A⁴. The base 50 A is provided with two parallel longitudinal grooves A⁵ and A⁶ in its upper surface, having the perpendicular outer edges A⁷ and A⁸. Secured in said grooves against the respective outer edges A⁷ and A⁸ are the strips A⁹ and A¹⁰. 55 These strips are provided with a series of corresponding transverse apertures A¹¹ and A¹². Arranged in alinement between the strips A⁹ and A¹⁰ and pivoting in the apertures A¹¹ and A¹² are a series of hinged septa B. Said septa 60 are preferably made from a single piece of spring-wire bent to form an enlarged rectangular base B', having the outwardly-extending portions B² and B³, adapted to spring into the apertures A¹¹ and A¹² and pivotally secure the 65 septa to the strips A⁹ and A¹⁰. The septa are also provided with the upwardly-extending handle B⁴, adapted to circumferentially restrain a disk B⁵, upon which is indicated a de- 70 sired letter of the alphabet. The lower edge 75 of the base B' is formed of the upwardly-ex- tending portions B⁶ and B⁷, which terminate centrally of said base.

The manner of using my device will be ap- 80 parent. The spaces between the septa vary 75 in size to suit the prevailing preponderence of names beginning with certain letters of the alphabet, and the space between said septa may be readily changed by simply compressing its base transversely in opposite direc- 85 tions, thereby removing the outwardly-extending portions B² and B³ from their respective pivot-sockets, when said septa may be moved the required distance and pivoted in its new position by releasing the compression of the 90 septa-base before mentioned. To assort pa- pers between any desired septa, it is only necessary to separate them by moving one about its pivot through the medium of the handle B⁴, thus permitting ready access to the 95 space therebetween.

It will be noted that while I have described a preferred form of my invention herein vari- 95 ous changes in details of construction and ar- rangement and combination of parts may be resorted to without departing from the scope of the claims.

Having thus described my invention, what I

claim as new, and desire to secure by Letters Patent, is—

1. In a device of the character described the combination with a base and supports therefor; of a series of septa detachably hinged to said base in horizontal alinement, each of said septa being formed of an integral piece of spring-wire.
2. In a mail-assorting device, a base provided with a central longitudinal groove having parallel sides, each of said sides being provided with corresponding apertures and a series of septa adapted to normally spring into and pivot in said apertures.
3. In a mail-assorting device, a base provided with a longitudinal groove, having parallel sides, each of said sides being provided with corresponding apertures and a series of septa adapted to normally pivot in said apertures and capable of transverse compression whereby same may be removed from pivotal connection with one corresponding set of ap-

ertures and pivotally connected with another corresponding set of apertures at will.

4. In a device of the character described the combination with a base and supports therefor; of a series of septa each constructed of an integral piece of wire bent to form an enlarged base and an upwardly-extending handle adapted to support an indicating-disk and means for pivotally connecting said septa to the base in horizontal alinement.

5. In a device of the character described the combination with a base and supports therefor; of a series of septa pivotally connected with said base in horizontal alinement and adapted to be released by compression from said pivotal connection.

In testimony whereof I affix my signature in presence of two witnesses.

JOSEPH J. MARSH.
